UNITED STATES PATENT OFFICE.

JOHN ERIK PLATON, OF JONKOPING, SWEDEN.

WRITING AND DRAWING PENCIL.

Application filed September 14, 1926, Serial No. 135,476, and in Sweden September 4, 1925.

The given invention relates to a writing and drawing pencil with changeable pencil leads, aniline or the like, which are shoved forward to the pencil point or tip from a magazine in the pencil by means of an actuating member such as a pin or the like. In known pencils of this kind the means for feeding the lead forward into writing position and the storing of the leads in the pencil are more or less complicated and unpractical, whereas insertion of new leads into the magazine is both inconvenient and time-wasting. The invention purposed to produce a pencil, which by its exceedingly simple construction and its sure and convenient operations avoids said inconveniences.

In the accompanying drawing are shown some suitable embodiments of the invention. Figs. 1 and 2 show the pencil from two opposite sides with the lead in writing position. Fig. 3 is a view of the pencil, corresponding with Figure 1, wherein the lead may be considered used up and the actuating member or pin shoved back a bit in order to allow a new lead from the magazine to come into feeding position for the member or pin. In Figures 4-12 the pencil is shown taken apart. Thus Figure 4 shows the magazine tube, and Figs. 5, 6, and 7 show from three different sides the tip and a guiding member for the member or pin connected therewith. Figs. 8 and 9 show, the latter in longitudinal section, a button or end-screw. Figs. 10, 11 and 12 show the actuating member or pin, Figure 11 being drawn in larger scale than Figures 10 and 12. Fig. 13 is a cross-section, taken on the line 13-13 of Figure 2. Fig. 14 shows a modified embodiment of the tip and the guiding member for the actuating member or pin. Figures 15-19 show another embodiment of the invention. Figure 15 is a side view of the tip and the guiding member for the actuating member or pin, which guiding member is joined to the tip. Fig. 16 shows in larger scale the outer end part of the guiding member. Figure 17 is a plan view of the parts according to Figure 15 with the end screw inserted in its place. Figures 18 and 19 are cross sections on the lines 18-18 and 19-19 of Figure 15.

The pencil is composed of four parts, namely the tip 1, which is provided with a longitudinal guiding member 9 extending

to the rear of the pencil, a pin 2 with a suitable actuating member 13, a magazine tube 3 and a button or end screw 4. The tip 1, Figures 5 and 6, which is preferably of conical form, is solid and provided with a central bore or channel 5 and is slit from the point a distance inwards, so that two resilient members or tongues 6 are formed, Figure 6. These members or tongues have as object, to hold the lead 7 in the tip. Because said members or tongues lie yieldingly against the lead, the latter may be moved into or out of writing position without being spoiled. The tip 1 is provided with a hole 8 passing completely through it, transversely, through which hole, when a new lead is to be moved forward to the pencil-point, may be observed if the lead has come in to the bore or channel 5. As above pointed out, a guide member 9 is provided, which is formed integrally with the tip 1, and is indicated at 9, Figures 6 and 9. The guide 9 is perforated by a central longitudinal slit 10, Figure 7, which extends along the entire length of the guide and is widened into a groove 11, Figures 5 and 13, which is situated substantially in the axis of the pencil and in alignment with the bore or channel 5 in the tip 1.

The pin 2 is slidably arranged in the groove 11 and provided with an actuating member in the form of a semi-spherical lug or the like 13 having a web portion, 12, Figures 10 and 11, slidably engaged in the slit 10. The member or lug 13, which at the movement of the pin slides against one side 14 of the guide 9, catches into corresponding threads on the inner side of the magazine tube 3, which encloses the guide 9, the curved face of the actuating member or lug 13 being provided with mutilated threads, substantially as shown for the purpose. The inner side of the tube rests against a neck 15 on the forward part guide and at the rear against an enlargement 17 on one side 16 of the guide. By turning the tube 3 in either direction, the member or pin is moved forwards or backwards in the groove 11 and is guided thereby by the web portion 12 of the part 13 engaged in the slit 10. As is evident of Figure 13, one side 16 of the guide, toward which the groove 11 is open, is situated at such a distance from the tube wall, that a comparatively large magazine 18,

Figure 13, is formed for the storing of the pencil leads, whereby the guide-side 16 serves as a bottom in said magazine. Between the guide side 14 and the magazine tube 3 is a space, Figure 13, closed off from the lead magazine 18 in which space the part 13 is movable. The slit 10 and the groove 11 merge rearwardly into a threaded hole 19, Figures 5 and 6, formed in the outer end of the enlargement 17, into which hole the button or end screw 4 is inserted, Figures 1-3. This button or screw is provided with a central bore 20, Figure 9, which is joined to the groove 11, so that the pin 2 may be moved out a distance through said bore, when a new lead is to be moved into feeding position for the pin. It is to be here noted that the slit 10, which opens into the bottom of the lead receiving groove 11, is narrower than the diameter of the lead to be used in the pencil.

According to the modification shown in Figure 14 the guide 9 is arranged in such a way that the magazine for the leads is larger. The groove in the guide is here not placed in the middle of the pencil, and for that reason the channel 5 may not go through the axis of the tip either. It is evident from the drawing that by this embodiment the tip is not tapering equally towards the point round its entire circumference. This however does not detrimentally affect the writing.

When a lead is used up and a new one is to be moved into writing position, the tube 3 is turned in such a direction that the pin 2 is shoved backwards through the bore 20 in the end screw 4, until the lug 13, on the pin, the web portion 12 of which member is 35 slideable in the slit 10, butts against the inner end of the screw 4, Figure 3. During this operation the pencil should be held in such a way, that that side of the guide indicated by 14 is turned upwards, Figures 1 and 3. In order to indicate this position the tip is provided with the number 1. When the pencil is held in this manner, the side of the guide indicated by 16 and thereby also the groove 11 are turned downwards, so that 40 the leads in the magazine lie against the inner side of the tube 3. In this position no lead may enter the groove and also thus prevent the shoving outwards of the pin. By the pushing backwards of the pin, the forward part of the groove 11 is liberated, so that, when the pencil is turned completely round and the side 16 of the guide is 45 turned upwards, a new lead may fall into the groove in front of the forward end of the shoved back pin. The last mentioned position of the pencil, which is shown in Figure 2, is indicated by the number 2 on the tip. Thereafter the point of the pencil is turned downwards, so that the lead, which 50 came into the groove, may slide down into

the channel 5 in the tip. After it has been observed through the hole 8 that the lead has really entered the bore or channel 5, the pin 2 is moved forward in the groove 11 by turning the tube 3, whereby its forward end shoves the lead forward into writing position. When one wishes to move the lead backwards in the tip, the tube 3 is turned so that the pin is shoved a little backwards in the groove, whereafter the forward end 75 of the lead may be pressed into the tip, where the lead is held by the resilient members or tongues 6.

When new lead shall be put into the magazine 18, which is seldom necessary as the magazine holds a great number of leads, the pin 2 should be shoved so far forward, that the threaded member 13 present on the pin, lies against the neck 15 on the guide. Thereafter the button or end screw 4 is taken 85 away, so that the leads one by one may be put into the magazine 18 through the hole 19 and the groove 11 joined thereto, the rear part of which groove is liberated 90 through the shoving forward of the pin. In the position of the pin just described, when the member 13 lies against the neck 15, the pin reaches so far back in the groove that although it permits the insertion of new leads into the magazine, it prevents a lead 95 in the magazine from falling into the groove. During the insertion of the leads the pencil is held so that the side 16 of the guide, against which the groove 11 is open, is turned 100 downwards, Figures 1 and 3, so that the leads, in the order in which they are inserted, fall out of the groove down against the inner wall of the tube 3. To facilitate the insertion of the leads, the pencil should naturally be held slanting with the point 105 downwards. When the magazine is filled, the end screw 4 is put into its place and the pin is shoved backwards (the side 16 of the guide should still be turned downwards) in order to leave place for a lead in the groove 110 in front of the end of the pin. The inserting of the lead in the groove and its being shoved forward into writing position takes place in the manner formerly described.

According to the embodiment shown in 115 Figures 15-19, one side 16 of the guide 9, which side is turned against the lead magazine, is provided with a shoulder or the like situated beside the lead groove 11, which in the shown embodiment consists of a projecting member 21, which stretches from the forward part of the guide 9 for a good distance backwards, and is provided with a shoulder edge 22 along the groove. Instead of the longitudinal shoulder edge the 120 guide can be provided with two or more projections, which form shoulders. The idea of this arrangement is to facilitate the insertion of a new lead in the groove 11 when a lead is finished. When the lead in 125 130

the magazine rolls against the shoulder edge 22, it falls immediately down into the groove. For this reason one can place a new lead in the pencil point very quickly.

5 On the same side of the guide 9 as the part 21 a thin plate or bridge 23 is situated above the groove, which plate 23 stretches from the rear end of the longitudinal member 21 to the swelling 17 and closes that 10 part of the groove from the lead magazine. When the pin 2 is shoved far forwards against the pencil point, no lead therefore (be it whole or broken) from the magazine can fall down into the groove 11 back of the 15 pin and hinder the pushing back of the pin, for instance when one shall make space for a new lead in the groove in front of the forward end of the pin.

The hole 19 for the end screw has according to this embodiment considerably greater 20 diameter than in the embodiment first described and extends through the entire member 17, so that new leads may after the end screw has been removed, easily be inserted 25 through the hole 19 on the plate or bridge 23 into the magazine. After the end-screw has been screwed in the hole 19, it prevents the leads in the magazine from falling out.

It is evident, that the described arrangements could be altered in many respects, without deviating from the important characteristics of the invention.

Having now particularly described and ascertained the nature of my invention, I 35 declare that what I claim is:

1. A writing and drawing pencil with changeable leads, which are adapted to be fed forwardly to the pencil tip from a magazine situated in the pencil by means of a 40 member, characterized by the fact, that the member is movable in a groove in an elongated guiding member which extends from a tip at the forward part of the pencil to a joint adjacent the rear part of the pencil

and which guiding member forms a bottom 45 in the magazine which extends approximately the entire length of the guiding member so that the leads in the magazine lie immediately beside and above the groove, but are prevented from entering the latter 50 by the member, except when the latter is moved rearwardly, when a lead from the magazine may fall into the groove in front of the member.

2. A writing and drawing pencil according to claim 1, characterized by the fact that the magazine is so arranged in the pencil that new leads, when the member is moved to a forwardly disposed position, may be inserted in the magazine through the groove 60 and a hole aligned therewith situated in the rear end of the pencil, without necessitating the pencil's being taken apart.

3. A writing and drawing pencil according to claim 1, characterized by the fact that the member is provided with an offset member disposed in engagement with the inner side of the magazine tube which is adapted to be rotated to move the member forwardly and rearwardly of the same.

4. A writing and drawing pencil according to claim 1, characterized by the fact that the guiding member is provided with one or several shoulders situated beside the lead groove which, when the member is in a rearwardly disposed position, acts to facilitate the insertion of a new lead into the groove after a lead is finished.

5. A writing and drawing pencil according to claim 1, characterized by the fact that the rear part of the lead groove is closed off 80 from the magazine, so that no lead from the magazine may fall into the groove back of the pin member when the latter is moved to a forward position adjacent the pencil point.

In witness whereof, I have hereunto signed my name.

JOHN ERIK PLATON.
